[57] CLAIM

The ornamental design for an identity tag reader, as shown and described.

DESCRIPTION

FIG. 1 is a front, side perspective view of an identity tag reader showing our new design;
FIG. 2 is an enlarged top plan view thereof;
FIG. 3 is an enlarged side elevational view thereof opposite that shown in FIG. 1;
FIG. 4 is an enlarged front elevational view thereof;
FIG. 5 is an enlarged rear elevational view thereof;
FIG. 6 is an enlarged bottom plan view thereof.
